UNITED STATES PATENT OFFICE.

ALVAN A. ALLAN AND EDWARD T. ELLIOTT, OF EVERETT, WASHINGTON.

WRENCH.

1,126,336.

Specification of Letters Patent.

Patented Jan. 26, 1915.

Application filed November 4, 1913. Serial No. 799,204.

To all whom it may concern:

Be it known that we, ALVAN A. ALLAN and EDWARD T. ELLIOTT, citizens of the United States, residing at Everett, in the 5 county of Snohomish and State of Washington, have invented new and useful Improvements in Wrenches, of which the following is a specification.

The present invention relates to that class 10 of wrenches commonly known as monkey wrenches and the primary object of the invention is to construct a wrench that is susceptible to quick adjustment and which will be effectively sustained at said adjustment 15 for operating upon an article but which also may be easily released from engagement with the article.

A further object of the invention is the provision of a wrench which includes a 20 slideable and movable jaw, the said slideable jaw being provided with a toothed member that normally contacts with the toothed shank of the stationary jaw and which is normally retained in such engagement through the me- 25 dium of a spring, the movable jaw being further provided with an adjusting element which will move the said jaw toward or away from the stationary jaw after the jaw has been locked upon the shank of the sta- 30 tionary jaw.

A still further object of the invention is the construction of a wrench which shall embody the desirable features of simplicity, cheapness to manufacture, effectiveness and 35 strength.

With the above and other objects in view, the invention consists in the construction, combination and arrangement of parts set forth in the following specification and fall- 40 ing within the scope of the appended claim.

In the drawings: Figure 1 is a side elevation of a wrench constructed in accordance with the present invention, Fig. 2 is a transverse sectional view on the line 2—2 of Fig. 45 1, Fig. 3 is a similar sectional view showing the arrangement of the locking member when its teeth are brought out of engagement with the teeth of the shank of the stationary jaw, and Fig. 4 is a horizontal sec- 50 tional view on the line 4—4 of Fig. 1.

Referring now to the drawings in detail, 1 designates the wrench in its entirety, the said wrench including a stationary jaw 2 which is formed with a right angular shank 3 which provides the handle for the wrench, and a jaw 4 mounted for slideable movement

upon the shank 3. The shank has its upper face at a distance from its head 2, provided, for a suitable distance, with transversely ar- 5 ranged teeth 5, the said teeth having one of their side walls beveled toward the head 2, and their opposite side wall vertically straight. The movable jaw 4 includes a head 6, to which is integrally formed a carriage 7. The carriage and head have their lower 65 portions provided with a rectangular open- 60 ing, so that the jaw 4 may be readily slid upon the shank 3 of the jaw 2. The carriage, above its longitudinal shank-receiving pas- 65 sage is provided with a transverse opening 8 70 which communicates with the said longi- 70 tudinal passage, the lower wall of the opening being disposed longitudinally of but be- 75 low the teeth 5. The inner transverse wall provided by the opening 8, or the wall ad- 75 jacent the head 6 of the jaw 5, is formed with an annular longitudinally extending depression or pocket 10, while the outer wall 11 provided between the opening and the end of the carriage is formed with a longi- 80 tudinally extending annular passage 12. The passage and pocket are adapted to re- 80 ceive the non-threaded portions 13 and 14 of a headed screw member 15. The threads 16 of the said screw are adapted to engage 85 within the threaded bore 17 of a rounded latch member 18. This latch member has a portion of its perimeter milled, as at 19, and is further provided with a straight longi- 90 tudinally extending portion 20 that is 90 formed with transverse teeth 21, the said teeth adapted to co-act with the teeth 5 of the shank 3 to lock the movable jaw upon the said shank. What may be termed the rear portion of the annular latch or lock 18 95 is provided with a recess 22 which is formed with an opening adapted for the reception of a headed securing element 23 whereby a bowed leaf spring 25 is connected with the member 18, the opposite end of the spring 100 being slidably mounted in the opposite end of the recess 22. The spring is arranged in the recess 22 with its bowed portion in fric- 100 tional contact with the walls of the opening 9, so that it will yieldably hold the lock 105 member 18 in an inoperative position when the serrated portion thereof is turned to bring its teeth 21 out of engagement with the teeth 5 of the shank of the stationary jaw when adjusting the movable jaw, and will 110 also yieldably hold the lock against move- 110 ment when it is in an operative position for

engaging the teeth thereof with the teeth of the stationary jaw.

It will be readily noted that the screw 15 will act directly upon the carriage or movable jaw 4 when the lock engages with the teeth of the shank so that a minute adjustment of the said jaw 4 may be obtained, and in order to sustain the movable jaw upon the shank 3, we provide the said shank at a suitable distance from its teeth 10 with a threaded opening, for the reception of a suitable member in the nature of a headed screw 26.

From the above description, taken in connection with the accompanying drawings, the simplicity of the device as well as the advantages thereof will, it is thought, be perfectly apparent to those skilled in the art to which such inventions appertain without further detailed description.

Having thus described the invention, what we claim is:

In a wrench of the class set forth, a stationary jaw having an angular shank provided with threads, a movable jaw arranged upon the shank, said movable jaw including a head and a carriage, the carriage having

a transverse opening, a headed threaded member arranged in the carriage and positioned approximately centrally and longitudinally of the opening of the carriage, a rotatable lock provided with a recess extending part way around the periphery thereof and a threaded bore, arranged within the opening in the shank and engaged by the threads of the screw, said lock having a series of teeth projecting outwardly from a portion of its periphery for engagement with the threads on the annular shank, a leaf spring having its ends seated in the recess of the lock and its intermediate portion bowed outwardly beyond the periphery of said lock for holding the latter from rotating when its teeth are in engagement or disengagement with the teeth formed on the shank.

In testimony whereof we affix our signatures in presence of two witnesses.

ALVAN A. ALLAN.
EDWARD T. ELLIOTT.
